[57] CLAIM

The ornamental design for a transparent cylindrical container, as shown and described.

DESCRIPTION

FIG. 1 is a perspective view of a transparent cylinder container showing my new design.

FIG. 2 is an enlarged front elevational view thereof; the rear being identical.

FIG. 3 is a side elevational view of FIG. 2; the opposite side being identical.

FIG. 4 is a top plan view of FIG. 2.

FIG. 5 is a bottom plan view of FIG. 2; and

FIG. 6 is an enlarged sectional view of FIG. 2 taken on line 6—6.
